E. P. SELDEN & H. S. PELL, JR.
PORTABLE STEAM BOILER.
APPLICATION FILED MAY 25, 1915.

1,197,673.

Patented Sept. 12, 1916.

UNITED STATES PATENT OFFICE.

EDWARD P. SELDEN, OF ERIE, AND HARRY S. PELL, JR., OF EAST MILLCREEK TOWNSHIP, ERIE COUNTY, PENNSYLVANIA, ASSIGNEES TO ERIE CITY WORKS COMPANY, OF ERIE, PENNSYLVANIA, A CORPORATION OF PENNSYLVANIA.

PORTABLE STEAM-BOILER.

1,197,673.

Specification of Letters Patent. Patented Sept. 12, 1916.

Application filed May 25, 1915. Serial No. 30,423.

To all whom it may concern:

Be it known that we, EDWARD P. SELDEN and HARRY S. PELL, Jr., citizens of the United States, residing in Erie and East 5 Millcreek township, respectively, county of Erie, and State of Pennsylvania, have invented new and useful Improvements in Portable Steam-Boilers, of which the following is a specification.

10 This invention relates to portable steam boilers and consists in certain improvements in the construction thereof as will be herein-after fully described and pointed out in the claims.

15 More particularly the invention relates to the lining for a furnace for an upright cylindrically-shaped portable boiler.

The invention is illustrated in the accompanying drawings as follows:—

20 Figure 1 shows a vertical section on the lines 1—1 in Fig. 2. Fig. 2 a section on the line 2—2 in Fig. 1. Fig. 3 a section on the line 3—3 in Fig. 1. Fig. 4 a perspective view of one of the bricks forming the lining.

25 Fig. 5 a perspective view of the top layer of the bricks of the lining.

1 marks the shell of the boiler, 2 the top flue sheet, 3 the bottom flue sheet, and 4 the flues. The boiler shell is continued with a 30 cylindrical furnace shell 5 surrounding the boiler furnace 6. The furnace is provided with the usual grate 7 and opening 8.

The lining is formed of brick having an outer surface preferably flat so that their 35 outer surfaces are of a contour varying from the contour of the cylindrical shell so as to form insulating spaces between the outer faces of the brick and the shell. Preferably the bricks have their outer surfaces 10 flat 40 and this in conjunction with the curve of the shell forms the insulating spaces. The bricks are also preferably formed with their ends 11 at right angles to their outer surfaces and when assembled in the shell this leaves

45 prism-shaped spaces between the ends of the bricks which also insulate the shell. The bricks are provided with the notches 12 in their ends and the rods 13, preferably in the form of pipe extend vertically through 50 the lining and are arranged in these notches thus keying the bricks in place. Washers 14 are arranged on the upper ends of the rods and heads or nuts 15 are arranged on the rods above the washers. The lower ends

of the rods extend through an angle iron 16 which is arranged around the bottom of the shell and forms a support for the lining. Nuts 17 are arranged on the bottom of the rods by means of which they may be drawn up so as to give support to the lining. The 55 upper course of bricks have the notches 18 to receive the washers 14 and nuts 15 and also have the annular groove 19 into which is sprung a ring 20, the ring preferably being parted at one point as at 21 to permit its 60 insertion and springing outwardly to place when released, the ends abutting preventing the collapsing of the ring. It will be noted that the ring engages the nuts 15 and thus 65 when in place forms a support for the upper ends of the rods holding them in place. It will be understood that this lining is subjected to its greatest strain so far as displacement is concerned in the shipping of the 70 boiler and the ring 20 is particularly effective while the boiler is being shipped.

The tie rods clamp the brick on the supporting flange and in this respect assist in holding the lining in place for shipping purposes.

75 The spaces between the points of contact allow the shell to go and come. The freedom of expansion is particularly desirable where the shell is in continuation of the boiler, as the boiler is thus relieved of any strains 80 from this source.

85 What we claim as new is:—

1. In a portable steam boiler, the combination of a vertical boiler shell cylindrically-shaped and extended downwardly to form a 90 furnace shell below the boiler; and a lining for the furnace shell formed of bricks having their outer surfaces of a contour differing from the shell and contacting with the shell at points throughout the circumference 95 thereof to form insulating spaces between the outer surfaces of the bricks and the furnace shell.

2. In a portable steam boiler, the combination of a vertical boiler shell cylindrically-shaped and extended downwardly to form a furnace shell below the boiler; and a lining for the furnace shell formed of bricks in contact with the shell having their outer surfaces flat to form spaces between said 105 outer surfaces and the furnace shell.

3. In a portable steam boiler, the combination of a vertical boiler shell cylindrically-

shaped and extended downwardly to form a furnace shell below the boiler; and a lining for the furnace shell formed of bricks in contact with the shell having their outer surfaces flat and their end surfaces at right angles to the outer surfaces forming insulating spaces between the bricks and the shell.

4. In a portable steam boiler, the combination of a vertical boiler shell cylindrically-shaped and extended downwardly to form a furnace shell below the boiler; a lining for the furnace shell formed of bricks having their outer surfaces of a contour differing from the shell and contacting with the shell at points throughout the circumference thereof to form insulating spaces between the outer surfaces of the bricks and the furnace shell; and locking devices arranged at the ends of the bricks.

5. In a portable steam boiler, the combination of a vertical boiler shell cylindrically-shaped and extended downwardly to form a furnace shell below the boiler; a lining for the furnace shell formed of bricks in contact with the shell having their outer surfaces flat and their end surfaces at right angles to the outer surfaces forming insulating spaces between the bricks and the shell; and locking devices arranged between the ends of the bricks.

6. In a portable steam boiler, the combination of a vertical boiler shell cylindrically-shaped and extended downwardly to form a furnace shell below the boiler; a lining for the furnace shell formed of bricks having their outer surfaces of a contour differing from the shell to form spaces between the outer surfaces of the bricks and the shell,

said bricks having notched ends; rods extending vertically through the openings formed by said notched ends for keying the bricks in place; a head on the upper ends of the rods; a washer between the head and the bricks; and means for tightening the rods at the bottom thereof.

7. In a portable steam boiler of the vertical flue type, the combination of a vertical boiler shell cylindrically-shaped and extended downwardly to form a furnace shell below the boiler; a lining for the furnace shell formed of bricks; vertical tie-rods extending upwardly through the lining; and a collapsible ring arranged on the upper course of bricks and forming a support for the upper ends of the tie rods.

8. In a portable steam boiler, the combination of a vertical boiler shell cylindrically-shaped and extended downwardly to form a furnace shell below the boiler; a lining for the furnace shell formed of bricks in contact with the shell having their outer surfaces flat and their end surfaces at right angles to the outer surfaces forming insulating spaces between the bricks and the shell, said bricks having notches in their ends; and rods arranged in the spaces between the ends of the bricks and extending into said notches for tying said bricks in place.

In testimony whereof we have hereunto set our hands in the presence of two subscribing witnesses.

EDWARD P. SELDEN.
HARRY S. PELL, JR.
